SHOE

Beth Levine, 59 W. 12th St., New York, N.Y.

Filed Feb. 14, 1962, Ser. No. 68,818

Term of patent 3½ years

(Cl. D7—7)

FIG. 1

I claim:

The ornamental design for a shoe, substantially as shown.
